(57) **CLAIM**

The ornamental design for a rear bumper of car, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a rear bumper of car showing my new design;

FIG. 2 is a front elevation view;

FIG. 3 is a rear elevation view;

FIG. 4 is a side elevation view;

FIG. 5 is an opposite side elevation view thereof;

FIG. 6 is a top plan view;

FIG. 7 is a bottom plan view; and,

FIG. 8 is another perspective view thereof.
